United States Patent Office

Des. 210,353

Patented Mar. 5, 1968

210,353

BOTTLE

Richard L. Platte, Ann Arbor, Mich., assignor to Hoover
Ball and Bearing Company, Saline, Mich.

Filed Aug. 3, 1966, Ser. No. 3,318

Term of patent 14 years

(Cl. D9—147)

FIG. 1

FIG. 2

The dominant features of my design reside in the portions shown in full lines.

I claim:

The ornamental design for a bottle, as shown and described.
